UNITED STATES PATENT OFFICE

2,610,395

CUTTER HEAD OF A DRY-SHAVING DEVICE

Albertus van der Lee, Wilhelmus Lambertus Leo-nardus Vivie and Karel Reinout Hofland, Eindhoven, Netherlands, assignors to Hartford National Bank and Trust Company, Hartford, Conn., as trustee

Application July 2, 1946, Serial No. 681,010
In the Netherlands February 5, 1943

Section 1, Public Law 690, August 8, 1946
Patent expires February 5, 1963

2 Claims. (Cl. 30—43)

1

It has been suggested before that the cutter head of a dry-shaving apparatus should comprise a cutting plate supported in position at the outer edge as well as centrally and a cutter co-operating therewith and actuated so as to rotate about a shaft, the central support of the cutting plate being formed by a stud passing through the hollow shaft of the drive and supported itself upon a stationary component member of the drive. When supporting in position in this manner the advantage is ensured that the cutting plate, which due to the minute thickness is liable to harmful sagging, caused for example by vibrations, is considerably strengthened and is enabled to be less bulky than without central support.

The invention provides a construction more attractive in many respects in that with a cutter head comprising a cutting plate supported in position at the outer edge as well as centrally and also a cutter co-operating therewith, at least one of these component members being adapted to rotate on a shaft, the cutting plate is supported in position by or in some cases secured to a member which is fixed to the lateral wall of the device and leaves free one or more apertures, and the rotary member is actuated so as to oscillate about the shaft by one or more reciprocating arms extending through the said apertures.

In this case, the movable member may be either the cutting plate or the cutter and in some cases both component members may be actuated so as to oscillate in the above-mentioned manner. If only one of the two component members is actuated the other member may be caused to rotate about the said shaft. Thus, the invention firstly offers several possibilities, of which a choice may be made at will, with regard to an optimum combination so far as the operation of the cutter head is concerned, the central support ensuring an arrangement substantially free from vibrations and rendering possible comparatively large dimensions of the active flexible part of the cutting plate. By securing the support to the lateral walls of the cutter head or of the frame or the housing of the dry-shaving device a robust construction is obtained and the use of a cleanly manufactured hollow driving shaft having a supporting stud inserted in it with all the consequent disadvantages, inter alia lubrication, larger shaft diameter and so forth, is obviated.

In order that the invention may be clearly understood and readily carried into effect it will now be described more fully with reference to the accompanying drawing, in which two diagrammatically illustrated embodiments of the invention are shown.

2

Figure 1 is a diagrammatic view showing the position of the cutter relative to the central support for the cutting plate and the supporting frame for the central support

5 Figure 2 is a cross-sectional view of a shaver head in accordance with the invention.

Figure 3 is a bottom view of the shaver head shown in cross-section in Fig. 2.

Fig. 1 shows a cutter comprising a ring 1 and 10 three cutting blades 2 fitted thereto which is actuated so as to oscillate about an axis 5 by means of a U-shaped component member 3 in the direction of the arrow points of the arrow 4. Intermediate the upright limbs of the component 15 member 3 is arranged a beam 6 whose ends are secured in the lateral wall of the device. The beam has supported upon it a stud 7 whose end 8 serves to support in position the central part of the cutting plate not shown in this figure. It is obvious 20 from the figure that supporting in position is enabled by the restricted course of the cutter through an angle of less than 180°. Since in the case shown provision is always made for three cutting blades it is preferable that the course of 25 the oscillatory movement for covering the entire cutting surface of the cutting plate should extend through at least 120°.

Fig. 2 shows in detail a simple method for the 30 obtainment of an oscillatory movement. The cutter 10 arranged on the inner side of the cutting plate 9 is actuated so as to oscillate by means of an arm 12 extending through an aperture 11. The arm 12 forms part of a lever 13 which is pivoted to the supporting member 16 by a small bolt 14 and a washer 15. The central 35 part of the cutting plate is secured to the supporting member 16 by means of a screw 17 and a re-entrant part 18 and is thus firmly supported in position. The lever 13 is actuated so as to oscillate by means of a slot-like aperture 19 and a stud 21 mounted eccentrically on the rotary 40 driving shaft 20.

In addition, the cutter is centered on the 45 re-entrant part 18 of the cutting plate 9, the cutting plate and the supporting member 16 being jointly secured to the housing 23 by a nut 22.

As described hereinbefore, the cutting plate 9, the screw 17, the supporting member 16 and also the screw 14 and the arm 13 jointly form a 50 unitary piece in which a cutter 10 and a small spring 24 are enclosed.

What we claim is:

1. Dry-shaving apparatus comprising an open-ended tubular portion, a plate-shaped frame member having an edge portion positioned over the opening of said tubular portion and having a

central portion and being provided with an aperture intermediate said central and edge portions, a circular cutting plate member having an edge portion and a central portion and having the inner portion between said edge and central portions provided with a running surface, a cutter member interposed between said frame member and said cutting plate member and having teeth engaging the running surface of said plate member, a single means to secure both the edge portion of said frame member and the edge portion of said cutting plate member to said tubular portion, said cutter member having a central opening, said cutting plate having a reentrant part extending through the central opening in said cutter member, means associated with said reentrant part to rigidly secure and support the central portion of said cutting plate member on the central portion of said frame member, a rotatable driving member arranged within said tubular portion, and an oscillating lever member pivotally secured to said frame member and having a portion thereof eccentrically engaging said driving member and another portion thereof extending through said aperture and engaging said cutter member.

2. Dry-shaving apparatus comprising an open-ended tubular portion, a plate-shaped frame member having an edge portion positioned over the opening of said tubular portion and having a central portion and being provided with an aperture intermediate said central and edge portions, an annular cutting plate member having an edge portion and a recessed central portion and having the inner portion thereof intermediate said edge portion and said central portion pro-

vided with a running surface, a rotatable cutter member interposed between said frame member and said cutting plate member and engaging the running surface of said plate member, means to secure the edge portion of said frame member and the edge portion of said cutting plate member to said tubular member, means positioned within the central recessed portion of said cutting plate member to support said cutting plate member on said central portion of said frame member, a rotatable driving member centrally positioned within said tubular portion, a spring member arranged about said central supporting means and interposed between said frame member and said cutter member, and a lever member having an end thereof pivotally secured to said frame member, a central portion thereof eccentrically engaging said driving member, and an arm portion extending through said aperture and engaging said cutter member.
